SHOE SOLE

John F. Meredith, Malden, Mass., assignor to Converse
Rubber Corporation, a corporation of Massachusetts

Filed Apr. 28, 1964, Ser. No. 79,717

Term of patent 14 years

(Cl. D7—5)

FIG. 1 is a plan view of the bottom, or outer, side of a shoe sole embodying the design;

FIG. 2 is an enlarged cross-section taken along line 2-2 of FIG. 1; and

FIG. 3 is an enlarged cross-section taken along line 3-3 of FIG. 1.

The top, or inner, side of the shoe sole is plain.

I claim:

The ornamental design for a shoe sole, substantially as shown and described.
